DESIGN FOR A BICYCLE

Mayo E. Roe, Elyria, and Wilbur Henry Adams,
Cleveland, Ohio

Application April 6, 1936, Serial No. 61,975

Term of patent 14 years

To all whom it may concern:

Be it known that we, Mayo E. Roe and Wilbur Henry Adams, citizens of the United States, residing at Elyria, in the county of Lorain and State of Ohio, and at Cleveland, in the county of Cuyahoga and State of Ohio, respectively, have invented a new, original, and ornamental Design for a Bicycle, of which the following is a specification, reference being had to the accompanying drawing, forming part thereof, in which:

Figure 1 is a side elevational view of a bicycle

embodiment our design; Figure 2 is a top plan view of the bicycle illustrated in Figure 1 with the saddle removed; and Figure 3 is a sectional view, substantially as indicated by the line 3—3 of Figure 1, with the rear wheel removed for convenience of illustration.

We claim:

The ornamental design for a bicycle, substantially as shown.

MAYO E. ROE.
WILBUR HENRY ADAMS.
